H. S. ROCKWELL

STIRRUP CHAIR

Filed Dec. 29, 1923

FIG. 3

INVENTOR
HARVARD S. ROCKWELL

By Vaneh, Vaneh & Moore

ATTORNEYS.

UNITED STATES PATENT OFFICE.

HARVARD S. ROCKWELL, OF MINNEAPOLIS, MINNESOTA.

STIRRUP CHAIR.

Application filed December 29, 1923. Serial No. 683,384.

To all whom it may concern:

Be it known that I, HARVARD S. ROCKWELL, a citizen of the United States, resident of Minneapolis, county of Hennepin, 5 and State of Minnesota, have invented certain new and useful Improvements in Stirrup Chairs, of which the following is a specification.

The object of my invention is to provide 10 a stirrup chair for use in reinforced concrete beam structures which will permit the use of a standard uniform type of stirrup, dispensing with the many different forms usually required in the structural reinforcement and effecting a considerable saving in 15 the cost of the stirrups.

A further object is to provide a stirrup chair which will insure the stirrups and beam rods being placed in substantially the 20 same position with respect to the surface of the beam even though the stirrups are put in position by unskilled labor.

A further object is to provide a stirrup chair which will support the stirrups so that 25 they will always be uniformly and properly spaced from the outer surface of the beam and thereby fully protected by a concrete covering.

The invention consists generally in various 30 constructions and combinations all as hereinafter described and particularly pointed out in the claims.

In the accompanying drawings forming part of this specification,

Figure 1 is a sectional view through a 35 portion of a slab and interior beam construction showing my improved stirrup chair in position therein;

Figure 2 is a similar view showing the 40 invention applied to an exterior or lintel beam;

Figure 3 is a view corresponding to the 45 previous figures illustrating the invention applied to an inverted or rectangular beam;

Figure 4 is a perspective of the chair 50 ready for use;

Figure 5 is a similar view illustrating the 55 chair adapted for the exterior and inverted type of beam.

In the drawing, Figure 1, 2 represents a 60 form for a horizontal or flat slab forming the floor of the building. 3 and 4 are the vertical side walls of the depending form for the horizontal beam of the floor into

which the concrete is poured in the usual 55 way in the erection of the building. It has been customary to provide stirrups depending within the beam form and supporting horizontal reinforcing rods in the lower portion of the beam. These stirrups have been 60 supported in various ways usually by having downwardly turned end portions resting upon the bottom of the slab form and other means have been provided for supporting the stirrups, all requiring a different form of stirrup for use in different positions in the beam and floor structure, providing all these different forms of stirrups has added, of course, to the expense of the 65 reinforcement and the time and labor required in placing the stirrups in position. Then, too, unless the stirrups were carefully placed by a skilled workman, some would be out of position or too near the outer surface of the beam, or where the reinforcing 70 rods supported thereby would not be effective for the purpose designed. These stirrups usually are put in place by unskilled or incompetent workmen and very little 75 attention is paid to placing them uniformly in the form or where the reinforcing rods would be in position to be most effective. Sometimes the stirrups would be so near 80 the surface of the beam that the metal would be exposed to the elements and in such case, the reinforcing rods would be in 85 the same degree out of their proper position.

To eliminate this difficulty in the use of a 90 reinforcing rod supporting stirrup, I have devised a chair which not only will permit the use of a standard form of stirrup but will insure the proper placing of the stirrup and the reinforcing bars in the structure by an unskilled or incompetent workman. In 95 other words, if the stirrup is placed in its depending position in the beam, it must be properly placed with its depending legs uniformly spaced from the outer surface of the beam.

In carrying out my invention, I provide a 100 section of angle plate 5 having its lower portion provided with ears 6 turned outwardly to fit the inner surface of the form sides 3 and 4 and be secured thereto by suitable 105 means such as nails 7. Between these ears, the angle plate is cut away as indicated at 8 to provide openings through which the con-

crete may flow freely. The upper portion of the angle plate is preferably of solid construction projecting up through the form for the floor slab and its angle is provided 5 with a recess 9, the bottom of which is a suitable distance below the top of the floor slab and is adapted to receive the horizontal reinforcing rods 10 which extend through the floor slab above the beam on each side of the 10 beam form. The stirrup 11 has hooked ends 12 which are hung on the rods 10; the stirrups, depending within the beam, form a supporting means for a series of beam rods 13 which extend longitudinally of the form 15 near the bottom thereof. The angle plates or chairs 5 serve, therefore, not only as supports for the rods 10 and the stirrups 11 but as a spacing means insuring the uniform spacing of the legs of the stirrup from the 20 surface of the beam so that when the rods 10 are put in position, and there is only one place where these rods can be put, an incompetent or careless workman may put the stirrups in place and those in charge of the 25 work will know that each stirrup will be properly positioned with respect to the surface of the beam and the reinforcing rods will also be properly placed where they will be most effective as a reinforcing means. If 30 the chairs are fastened in the forms properly and this work will usually be done by a skilled workman, then there is no chance for an unskilled workman to improperly put the stirrups in position. Each one must be in 35 the same relative position in the beam when the work is completed and the same is true of the reinforcing rods 10 and 13.

In Figure 2, an exterior beam form 14 is 40 illustrated and here I provide a shorter or smaller form of chair 15, as shown in Figure 5, having flanges 16 secured to the inner face of the form in the same manner as described with reference to Figure 1. The recess in the angle of the chair is substantially 45 the same as shown in Figure 4, and I indicate it by the same reference numeral.

In Figure 3, a form 17 for an inverted beam is shown extending above the floor 50 slab and in this structure I provide a pair of chairs 15, corresponding to the one shown in Figure 5 which are arranged upon the opposite inner faces of the form; the stirrup being similar in construction but somewhat 55 narrower than the one shown in Figure 1. The manner of supporting it, however, in the beam is substantially the same and the reinforcing rods at the bottom of the beam are indicated by the same reference numerals. I am thus able with this form of 60 supporting chair to adopt a universal type of stirrup adapted for all the different forms of horizontal beams in reinforced concrete construction. I thus effect a considerable 65 saving in the cost of producing the stirrups

as well as in the installation of the same in the work.

I claim as my invention:

1. In a reinforced concrete beam construction, stirrup chairs adapted to be secured to the opposing inner faces of a form, rods arranged lengthwise of the form and seated in said chairs, and a stirrup having ends supported by said rods and depending within the form. 75

2. In a reinforced concrete beam construction, stirrup chairs angular in form adapted to be seated against opposing inner faces of a concrete beam form and secured thereto and having seats formed therein, beam rods fitting within said seats and extending lengthwise of the form, and stirrups having ends engaging said rods and depending within the form and spaced by said rods from the walls of the form. 80

3. In a reinforced concrete beam construction, stirrup chairs composed of sheet metal folded longitudinally to form flanges in angular relation to each other, said flanges having means for securing their edges to the inner opposing faces of a form and the junction of the flanges of said chairs being provided with diagonal recesses forming seats, and beam rods adapted to extend lengthwise of the beam form and fitting within said seats and supported thereby a uniform distance from the walls of the form, and stirrups composed of rods having parallel depending portions provided with hooked ends to engage said rods and be supported thereby, said chairs supporting said rods and stirrups in substantially the same relative position in the beams and spacing them uniformly from the surface of said beams. 90

4. In a reinforced concrete beam construction, stirrup chairs and longitudinal reinforcing beam rods having seats in said chairs and positioned thereby in the upper portion of the beam form, beam stirrups having ends supported by said rods and depending within the beam form and spaced by said rods and chairs from the walls of the beam form, and rods supported by said stirrups adjacent the lower walls of the beam form. 105

5. In a reinforced concrete beam construction, stirrup chairs adapted to be secured to the inner faces of a form and having stirrup supports and stirrups carried by said supports and depending within the form. 110

6. In a reinforced concrete beam construction, stirrup chairs adapted to be mounted on the inner face of a form, supports extending lengthwise of the form and carried by said chairs, and stirrups engaging said supports and depending within the form. 115

In witness whereof, I have hereunto set my hand this 22nd day of December, 1923.

HARVARD S. ROCKWELL.
